BABY'S RATTLE

Joseph Davis, Arlington, N. J.

Application March 24, 1939, Serial No. 264,023

6 Claims. (Cl. 46—193)

The following description deals with a novel improvement in baby rattles. One of the objects of the invention is to make from suitable thermoplastic material a rattle which will be safe and convenient for a baby to use. Such a toy should be capable of being held by both hands and readily reversible in position. It should supply a noise making device which will be safe for the child to use.

10 A further object of my invention is to provide a rattle which will have no sharp or projecting parts and which will be firmly assembled for strength and security against breaking or loss of parts.

15 A still further object of my invention is to add reinforcing or strengthening parts to the device at the points where it is likely to be subjected to the greatest strain.

20 A further object of my invention is to improve the method of assembly of such devices so that it may be made of thermoplastic material, the parts of which are either integrally assembled or automatically fastened together. As illustrating the improved embodiment of this invention, I have shown one form in the following drawing in which

Fig. 1 is a plan view of my improved baby rattle;

Fig. 2 is a vertical section on the line 2—2 of Fig. 1;

Fig. 3 is an exploded perspective view of the upper and lower shells with the contained bells in relative positions for assembly; and

Fig. 4 is a fragmentary cross-section of the assembled shells on the line 2—2 of Fig. 1.

25 The device consists essentially of two complementary hollow rings or shells 11 and 12 and sound producing members 13, 13 suitably held loosely within the enlargements formed on the rings 11 and 12.

30 The ring or shell 11 which for purpose of distinction will be referred to as the bottom ring is molded of thermoplastic material in a hollow or concave cross-section. As shown in Fig. 3 there is an outer wall 14 and an inner wall 15 giving the ring a hollow or trough-like form. Diametrically spaced around the ring are two hemispherical perforated cups or recesses 16. The important feature is that the upper edges of the walls 35 14, 15 and recesses 16 shall be in a common plane.

35 Transversely or upwardly extending from the bottom of the ring 11 are pins or projections 17. These are equally spaced around the ring 11. In the preferred form six of these pins are used with one pair diametrically disposed with respect to

the recesses 16 and the other pairs equally spaced bringing one pin on each side of each recess 16. The pins 17 extend slightly more than twice as high as the depth of the concavity in the ring.

40 The opposite complementary or upper ring 12 also has the side walls 14 and 15 and similar recesses 16. Instead of pins 17, the ring 12 has apertures 18 so spaced around the bottom of the concave ring as to register with and receive the pins 17 as indicated in Fig. 2.

The sound making devices 13 have been illustrated as spherical sleigh bells slightly smaller than the inside diameter of the recesses 16.

45 The assembly of the rattle is easily carried out by placing a bell 13 in each recess 16 of one ring section or shell. The complementary ring is then fitted upon the first ring. This brings the edges of the side wall 14 and 15 and of the recesses 16 into abutting relationship. Due to the length of the pins 17 they project through the apertures 20 18 and slightly beyond as indicated in Fig. 2. The free ends of the pins 17 are then attached to the opposite ring 12. This is easily accomplished by the addition of slight heat if the material is thermostatic. Otherwise a slight swaging operation will spread the end of the pin. In either event the fastening is accomplished by an increased frictional engagement between the side of the pins 17 and the aperture 18. Thus there are no projecting or rough surfaces produced.

50 Thus assembled the pins 17 provide reinforcements or struts firmly holding the two ring sections together with added strength against breakage. The position of the pins with respect to the recesses 16 give added strength at the points 35 where these enlargements would tend to weaken the rattle. Incidentally, the mode of attachment serves to force the edges 14 and 15 tightly together so that the same effect is obtained whether or not these edges are cemented together.

55 The opposite side portions of the rings provide easy hand grips. The rattle may be changed from one hand to the other and in any position in which it is grasped will present one or the other of the recesses 16 with the contained sound producing bell. It may thus serve not only as an attractive rattle but also as a teething ring.

It will be evident that it is within the purview of this invention to use suitable materials and to vary the minor details of operation and structure without departing from the scope of the following claims.

What I claim is:

1. A rattle comprising a ring of uniform cross-section and having spaced enlarged recesses and 55

a series of transverse pins, a second ring having similarly spaced enlarged recesses and a series of holes receiving said pins, and sound producing members loosely carried in said correlated recesses.

5. 2. A rattle comprising a ring concave in cross-section, a series of pins extending transversely of said ring, said ring having spaced enlarged recesses, a second ring concave in cross-section having similarly spaced enlarged recesses and having a series of holes receiving said pins, and sound producing members loosely carried in said correlated recesses.

3. A rattle comprising a ring concave in cross-section and having spaced enlarged hemispherical recesses, a second ring concave in cross-section and having similarly spaced enlarged hemispherical recesses, sound producing members loosely carried in said correlated recesses and means for fastening said rings together in abutting relationship.

4. A rattle comprising two complementary hollow rings, enlarged recesses formed by said rings,

sound producing means loosely carried in said recesses and reinforcing means integrally formed at spaced points on one ring for attachment to the other ring.

5. A rattle comprising two complementary hollow rings, diametrically spaced enlarged recesses formed by said rings, sound producing means loosely carried in said recesses, and reinforcing means integrally formed on one ring at spaced points between said recesses for attachment to the other ring.

6. A rattle comprising a ring of plastic material and concave in cross-section, said ring having spaced enlarged recesses, a series of transverse pins integral with the ring, a second ring of plastic material, concave in cross-section and having spaced enlarged recesses registerable with those of said first ring, and sound-producing members loosely carried in said correlated recesses, said pins being attached to the second ring at spaced points therearound.

JOSEPH DAVIS.
